COMBINED MIRROR AND LOCKER DOOR RECEPTACLE

Donald W. Byers, 5600 SW. Wilbard St.,
Portland, Oreg. 97219

Filed May 1, 1968, Ser. No. 11,737

Term of patent 3½ years

Int. Cl. D6—01

U.S. Cl. D33—3

FIG. 1 is a front view of the receptacle;
FIG. 2 is a side view of the same;
FIG. 3 is a top plan view of the same; and
FIG. 4 is a side perspective view of the same taken slightly from the front.

I claim:

The ornamental design for a combined mirror and locker door receptacle, substantially as shown and described.
